UNITED STATES PATENT OFFICE.

EDWARD WALTER, OF KEYTESVILLE, MISSOURI, ASSIGNOR OF THREE-FOURTHS TO WILLIAM C. GASTON, HENRY L. SNEED, AND MILLARD F. COURTNEY, OF KEYTESVILLE, MISSOURI.

BUGGY-TOP ATTACHMENT.

SPECIFICATION forming part of Letters Patent No. 757,161, dated April 12, 1904.

Application filed July 25, 1903. Serial No. 167,033. (No model.)

To all whom it may concern:

Be it known that I, EDWARD WALTER, a citizen of the United States, residing at Keytesville, in the county of Chariton and State of Missouri, have invented a new and useful Improvement in Buggy - Top Attachments, of which the following is a specification.

This invention relates generally to buggy-tops, and more particularly to certain improvements to Patent No. 719,538, granted to me February 3, 1903, the object of the present invention being to provide a simpler and newer means for unlocking the sliding sections of the rear uprights when it is desired to lower the top; and with this object in view the invention consists in the novel features of construction, combination, and arrangement, all of which will be fully described hereinafter and pointed out in the claims.

In the drawings forming part of this specification, Figure 1 is a perspective view showing the practical application of my invention. Fig. 2 is a front view of one of the uprights, showing the locking-catch applied thereto. Fig. 3 is a side elevation of the same. Fig. 4 is a detail sectional view showing the catch in engagement with the groove in the solid portion of the upright.

In a carriage-top constructed in accordance with my patent before referred to the end uprights consist of the tubular upper portions A and the solid lower portions B, the tubular portions sliding upon the solid portions when the top is lowered, and when the top is raised it is of course necessary to securely lock the sections against movement, and this I accomplish by means of the attachment forming the subject-matter of this application and which consists of a transverse locking-catch C, which is adapted to work through a transverse opening A', produced in the lower end of the tubular portion of the upright, and engage the transverse groove B', produced in the upper portion of the solid member. The catch C is carried at the lower end of the curved arms D, which are pivoted at D' to the rearwardly-extending portions E' of a casting E, secured

to the forward side of the tubular member A adjacent its lower end, and this casting also has a transverse opening E', which coincides with the transverse opening A' and through which the catch works. The arms D are connected by means of a curved yoke or member F, and it will be noted that the yoke, arms, and catch are all constructed from a single piece of metal, which is the preferred form of construction, although it will of course be understood that it may be constructed otherwise, if so desired.

A flat leaf-spring G is fastened to the casting E adjacent its upper end, the free end of said spring bearing upon the catch C and normally holding it in the opening A', and it will be understood that when the transverse groove B' is brought into alinement with the opening A' the catch will engage said groove and being held in engagement by means of the spring will securely lock the tubular and solid members together. For the purpose of disengaging the catch when it is desired to lower the top I employ a rod H, which is connected at its lower end to a central portion of the yoke F and at its upper end is connected to a hand-lever I, adjacent its pivotal end, said lever being rigidly connected to a cross-rod K, which is journaled at each end in the members J, one of the said members being shown in detail in Fig. 4 of my patent previously mentioned, and by having the levers rigidly connected it is obvious that the operation of one lever at one side will operate the lever and parts connected therewith at the opposite sides. It will also be understood that as each end upright consists of a tubular and solid portion each one will be provided with a catch and operating mechanism.

It is obvious from the construction of the device that it can be operated either from within a buggy or carriage or from the ground. When the top is raised, the catch will automatically engage the transverse groove of the solid portion, and when it is desired to lower the top it is only necessary to swing the lever upwardly, thereby withdrawing the catch

from the transverse groove, and the top can then be folded.

Having thus fully described my invention, what I claim as new, and desire to secure by 5 Letters Patent, is—

1. The combination with the tubular and solid members of the upright, the tubular member having a transverse opening and the solid member a transverse groove, of the 10 spring-actuated catch carried by the tubular member adapted to engage the transverse groove of the solid member, and the lever and rod for operating the said catch, as specified.
2. The combination with the tubular member having a transverse opening, of the solid member having a transverse groove, the casting having a transverse opening, the catch pivoted to the casting, the spring carried by 15 the casting and bearing upon the catch, and

the lever and rod for operating the catch, as 20 specified.

3. The combination with the tubular member having a transverse opening, of the solid member having a transverse groove, the casting having a transverse opening coinciding 25 with the transverse opening in the tubular member, the catch, the arms carrying the catch and pivoted to the casting, the yoke connecting the arms, the leaf-spring connected to the casting and bearing upon the catch, the 30 lever and the rod connecting the lever and yoke, all arranged and adapted to operate substantially as shown and described.

EDWARD WALTER.
